SHIPPING CARTON

John Albert Buser, Lebanon, Pa., assignor to Lebanon Paper Box Company, Lebanon, Pa., a corporation of Pennsylvania

Application November 23, 1938, Serial No. 241,945

12 Claims. (Cl. 229—32)

This invention relates to shipping cartons, and more particularly to a carton comprising a collapsible box body which may be shipped to the user in collapsed substantially flat position, the user thereafter erecting the box into container-forming position to receive the merchandise. The invention further comprehends the provision of one or more merchandise-supporting and retaining members which the user may insert into the box body for retaining the merchandise in proper fixed position within the container body.

In accordance with my invention, a box body is provided which may be formed from a single blank of paperboard material which may be cut substantially rectangular in shape with a minimum of waste of paperboard material, which body-forming blank may be cut and scored preparatory to assembly on an automatic cutting and scoring machine at a high production rate. The box body generally comprises a bottom wall panel and enclosing side and end wall panels hinged thereto, the enclosing panels being suitably connected at the corners by means of securing flaps or edging strips. The opposite end walls are each provided with a fold or score line extending diagonally from one lower corner of the box body upwardly in a straight line to the upper edge of the end wall panel. One of the side wall panels is provided with a pair of diagonally extending and converging score lines which extend from the opposite lower corners of the box upwardly to the upper edge of the side wall panel. As thus formed, the scored side wall panel is divided into a central collapsing section adapted to be folded inwardly so as to overlie the bottom wall panel and end sections folded inwardly so as to overlie the central collapsing section of the side wall section. The diagonally extending fold line traversing each end wall panel divides each end wall panel into two collapsing sections, one of which sections may be collapsed inwardly to overlie the inside face of the adjacent end section forming a part of the scored side wall panel, and the other end wall section being then folded so as to overlie its companion end wall section, thus permitting the opposite unscored side wall section to be folded downwardly so as to overlie the adjacent end wall sections to which it is connected, providing a substantially flat collapsed box body. A plurality of such collapsed box bodies may be stacked together so as to occupy a minimum of space during shipment and storage.

When the user desires to place merchandise in the box, the same can be erected into con-

tainer-forming position by merely erecting the side wall panels into a position substantially at right angles to the bottom wall panels. That side wall panel which is provided with the converging and diagonally extending fold lines, is provided with a lip or flap portion hinged to the upper edge thereof which may be turned inwardly after the merchandise has been inserted into the box body, which lip portion serves thereafter as a bracing and reenforcing strut which prevents inward collapse of the side and end wall panels of the box. To further reinforce and strengthen the construction, a similar lip portion may be hingedly connected to the upper edge of the other side wall panel and also to the upper edge of each of the scored end wall panels.

If the merchandise is of a fragile nature so as to be susceptible to damage in shipment, I provide one or more merchandise-containing and supporting insert members which may be telescoped into the erected box body. Each insert is provided with a merchandise-supporting platform having an area substantially co-extensive with the interior cross-sectional area of the box body. Each platform is provided with downwardly extending supporting flanges which may rest upon the bottom wall panel of the box so as to maintain the platform in the proper spaced relation to the bottom wall panel. Each platform may have a merchandise-receiving opening cut therein, the peripheral edges of said opening being shaped to substantially conform to the contour of the merchandise, thus retaining the merchandise out of contact with the side and end wall panels of the box body and also, if desired, out of contact with the bottom wall panel and the cover panel of the box. The cover panel may be hingedly connected to one of the platforms by means of a spacing section which lies adjacent the inside face of one of the enclosing walls of the box. When the cover panel is in closed position the facing section is maintained in close abutting relation with the adjacent enclosing panel, thus further reenforcing and strengthening the box-enclosing walls against inward collapse. The cover panel may be provided with flanges which telescope over the exterior surface of one or more of the enclosing panels of the box body or it may be provided with one or more insertion flaps hinged thereto which may be inserted into the box interior.

An object of this invention is to provide a highly serviceable carton for the packaging of various articles of merchandise which can be

economically formed and constructed and which presents a box body which may be shipped to and stored by the user in collapsed substantially flat position, which can be quickly erected into 5 container-forming position to receive merchandise by the user as needed, which box body is provided with means associated therewith which can be quickly adjusted by the user to thereafter prevent inward collapse of the enclosing side 10 walls thereof.

Another object of this invention is to provide a box body which can be economically constructed and manufactured from a single blank of paperboard material substantially entirely by 15 automatic machinery at low cost, which box body is provided with means to effect substantially flat collapse of the enclosing side walls thereof for shipment and storage purposes and which thereafter may be erected by the user as needed 20 to receive the merchandise therein, means being provided to retain the enclosing side walls in rigid erect merchandise-enclosing and protecting position.

Another object of this invention is to provide 25 a shipping carton comprising a box body having associated therewith a merchandise-retaining and supporting insert so constructed as to retain the merchandise in fixed, spaced relation relative to the enclosing side walls of the box body, 30 thus to protect the merchandise packed therein against damage during shipment.

Still another object of this invention is to provide 35 a merchandise-supporting member adapted to be inserted into a box body, which member comprises a merchandise-supporting platform having merchandise-engaging means to retain the merchandise in fixed position within the box body, said merchandise-supporting member having a box cover formed as an integral part 40 thereof.

Other objects of this invention will become apparent as the disclosure proceeds.

Various other features and advantages of the 45 invention will be apparent from the following particular description and from an inspection of the accompanying drawings.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings 55 forming a part thereof, in which:

Fig. 1 is a face view of a prepared blank from which my improved collapsible box may be made;

Fig. 2 is a face view of a prepared blank which 60 when assembled is inserted into the set-up box from the blank shown in Fig. 1 to provide a combination merchandise-supporting platform and cover for the box;

Fig. 3 is a face view of a prepared blank which 65 when assembled and inserted into the set-up box provides a second merchandise-supporting platform;

Fig. 4 is a perspective view of a box as it appears when partially assembled from the blank 70 shown in Fig. 1;

Fig. 5 is a perspective view of the fully assembled box as it appears when undergoing collapse preparatory to shipment and storage;

Fig. 6 is a perspective view of a vertical stack 75 of collapsed boxes as they are arranged for shipment and storage purposes;

Fig. 7 is a perspective view of the combination merchandise-supporting and box cover member as it appears when assembled and ready to be inserted into the box;

Fig. 8 is a perspective view of the fully assembled erected box having one merchandise-supporting insert formed from the blank shown ready to receive the merchandise-supporting insert shown in Fig. 7.

Fig. 9 is a perspective view of the assembled 1 box with the merchandise-supporting inserts positioned therein, this view showing the cover arranged in partially closed position; and

Fig. 10 is a vertical cross-sectional view 1 through the packed carton taken along the line 10—10 of Fig. 9, showing in dotted line a piece of merchandise in the form of a candy toy positioned therein.

Similar reference characters refer to similar parts throughout the several views of the drawings and specification.

My improved collapsible box may be advantageously formed from a single blank A of paperboard material, as shown in Fig. 1. It will be noted that the blank A is substantially rectangular in outline and can be cut and scored to the desired shape and configuration at a high production rate, from large sheets or rolls of suitable cardboard material, by an automatic cutting and scoring machine. Each blank thus formed comprises a bottom wall panel 1, two side wall panels 2 and 4 each hinged to the bottom wall panel 1 along a score line 6, and two end wall panels 3 each hinged to the bottom wall 35 panel 1 along a score line 5, forming a box of four-sided configuration.

To permit substantially flat collapse of the box when assembled, a score line 7 extends across each of the end wall panels 3, dividing each panel 40 into two collapsing sections 3a and 3b. Each score line 7 extends from the meeting point of the score lines 6 and 5 to the top edge of the end wall panel 3, to form the generally triangular-shaped collapsing sections 3a and 3b. One 45 of the side wall panels 4 is provided with a pair of diagonally extending score lines 8 each extending from the meeting points of the score lines 5 and 6 and extending across the side wall panel in an inwardly converging direction to the 50 top edge of the side wall panel 4. The score lines 8 divide the side wall panel 4 into a central collapsing section 4a and two end collapsing sections 4b.

Side wall panel 2 is provided with a securing 55 flap 9 hinged to each end thereof along the score line 10. A securing flap 11 is hinged to the side edge of each end collapsing section 4b of the front wall panel 4 along the score line 12, which score line is substantially a continuation of and in 60 alignment with the score lines 5 and 10.

The side wall panel 2 may be provided with a lip portion 13 which extends substantially the full length thereof and is hinged thereto along the score line 14. The side wall panel 4 is also provided with a lip portion 15 which extends substantially the full length thereof and is hinged thereto along the score line 16. It will be noted by referring more particularly to Fig. 1 that the diagonally extending score lines 8 continue 70 through and to the outer edge of lip portion 15, dividing the lip portion 15 into a central lip section 15a and two end lip sections 15b. The complete box-forming blank A may be cut and scored to the form above indicated and as shown in Fig. 75

1, by an automatic cutting and scoring machine without hand labor.

In assembling the blank A into box form, a suitable glue or adhesive *g* is applied to the inside face of the end wall panels 3, which operation can be performed automatically by a spot gluing machine of well-known construction. This same machine operates to raise the side wall panels 2 and 4 into a position substantially at right angles to the bottom wall panel 1, then operates to fold the securing flaps 9 and 11 inwardly, as shown in Fig. 3, then operates to raise the end wall panels 3 into a position substantially at right angles to the bottom wall panel 1, and finally presses the securing flaps 9 and 11 into adhesive contact with the inside face of the adjacent end wall panels 3. The box as thus formed and ejected from the machine is fully assembled with the side and end wall panels in upstanding position.

It will be noted that the glued area *g* applied to the end wall panels 3 so as to secure the securing flaps 11 to the adjacent end panel sections 3a only, and it will be particularly noted that the securing flaps 11 are not to be adhesively secured to the end panel sections 3b. Likewise the securing flaps 9 hinged to the side wall panel 2 are adhesively secured to the end wall sections 3b only, and are not to be secured to the end wall sections 3a. To prevent the securing flaps 9 from being secured to the end wall sections 3a, the lower edge 9a thereof may be so cut as to coincide with the diagonal score lines 7 of the end wall panel, when the box body is erected, although it will be appreciated that the lower edge 9a can extend beyond and overlap the end wall section 3 if care is taken in applying the adhesive to the securing flaps 9 or to the end wall sections 3b to which they will be secured, so that the edge of this glued area terminates at the score line 7. Likewise, the securing flaps 11 hinged to the side wall panel 4 may be of such area as to overlap the end wall section 3b if the adhesive is so applied to the securing flaps 11 or the adjacent end wall sections 3a so that the adhesive intended to secure the securing flaps 11 to the end wall section 3 does not overlap or extend beyond the score line 7. This caution must be observed if the box is to collapse in a satisfactory manner.

After the box or carton has been assembled by the box manufacturer, it is shipped to the user in the collapsed position shown in Fig. 6, and the user packs the merchandise therein as needed. Since the erected box would occupy substantial space in shipment and storage, it is highly desirable that it be so constructed that it may be shipped and stored by the user in collapsed substantially flat position so as to occupy a minimum of space. My improved box is admirably adapted for such collapse. In collapsing the assembled box, the box manufacturer folds the central side wall section 4 into a position to substantially overlie the inside face of the bottom wall panel 1, as shown in Fig. 5. The end sections 4b of the side wall panel 4 will then fold so as to overlie the central section 4a; each end wall section 3a will fold so as to overlie the adjacent end section 4b; the end wall sections 3b will fold so as to overlie the end wall sections 3a, and finally the side wall panel 2 will collapse so as to overlie the end wall sections 3b, so that each box may be completely collapsed into substantially flat form, as shown in Fig. 6. In the collapsing operation it will be noted that the central lip section 15a will overlie the inside face of the bottom wall panel 1, and that the end lip

sections 15b will overlie the outside face of the central side panel section 4a, and the lip portion 13 will extend substantially coplanar with the collapsed side wall section 2 and overlie the inside face of the collapsed end wall sections 3a. 5 By adhesively securing the securing flaps 11 to the end wall sections 3a only and by adhesively securing the securing flaps 9 to the end wall sections 3b only, no difficulty is encountered in effecting a smooth and substantially flat collapse 10 of the box. Any desired number of collapsed boxes may be stacked together and thereafter bundled, wrapped, or boxed for shipment. It will be appreciated that a large number of collapsed boxes may thus be packed for shipping and storage in a relatively limited space. 15

When the user desires to pack an article of merchandise M within the box, the box is quickly erected by lifting the side wall panel 2 into a position substantially at right angles to the bottom wall panel 1 and then lifting the central section 4a of the side wall panel 4 substantially at right angles to the bottom wall panel 1. This last operation automatically brings the end sections 4b of the side wall panel 4 and the end wall 25 sections 3a and 3b of the end wall panels 3 into a position substantially at right angles to the bottom wall panel 1, providing an open, erected, four-side box which receives the merchandise. It will be noted by referring to Fig. 4 that a corner portion 11' of each unscored securing flap 11 extends over the fold line 1 and overlaps a portion of the adjacent end wall section 3b. This arrangement materially braces and strengthens the end wall panels against outward collapse 35 when the box is erected.

After the merchandise M has been packaged therein, the box may be maintained in rigid erect position by folding the lip portion 15 inwardly substantially at right angles to the side wall 40 panel 4. The lip portion 15 serves to brace and stiffen the side wall panel 4 so that the diagonally extending score lines 8 therein are ineffective to effect collapse of the box. A similar stiffening lip portion 13 provided on the side wall panel 2 45 is also turned inwardly substantially at right angles to the side wall panel 2 after the merchandise has been packed in the box. To further stiffen the construction, similar lip portions 17 may be hinged along the score line 18 to the 50 upper edge of each end wall panel 3, as shown in dotted lines in Fig. 7. If lip portions 17 are provided on the end wall panels 3, the diagonally extending score line 7 continues through the lip portions 17 dividing the same into lip sections 17a 55 and 17b. As thus constructed the lip portions 17 do not interfere with the full and satisfactory collapse of the box structure. It will be appreciated that normally the lip portion 15 when turned inward serves to maintain both end wall panels 60 3 as well as the side wall panels 2 and 4 in erect container-forming position, and the lip portions 17 hinged to the end wall panels 3 need only be provided if additional stiffness and strength is desired. 65

In the packaging of certain forms of merchandise it is desirable that the merchandise be held in fixed position within the box body so that it will not be damaged during shipment. One or more merchandise-retaining inserts may be positioned within the box body to retain the merchandise therein in fixed position. A cover for the box may also be formed as a part of one of the merchandise retaining inserts, which merchandise-retaining insert and cover may all be 75

formed from a single blank B of paperboard material, as illustrated more particularly in Fig. 2. This merchandise-retaining insert and cover assembly comprises a platform 21 having an area 5 substantially equal to the interior cross sectional area of the box body. The platform 21 is provided with spacing flanges 26 hinged to the side edges thereof along the score lines 27. The spacing flanges 26 are of such height as to rest upon the bottom wall panel 1 of the box, as shown in Fig. 10, so as to firmly support the platform 21 at the proper elevation within the box interior. An end spacing flange 28 equal in depth to the side spacing flanges 26 and hinged to the platform 21 along the score lines 29 may also be provided. The platform 21 may be provided with an opening o cut therein with peripheral edges 21a of the opening so shaped as to generally conform to the merchandise M positioned within the box. 10

20 A cover panel 23 is provided for the box, which is held in proper spaced relationship from the platform 21 by a spacing section 22. The spacing section 22 is hinged to one end of the platform 21 along the score line 24 and the cover panel 23 is 15 hinged to the spacing section 22 along the score line 25. An insert flap 30 may be hinged to the other end of the cover panel 23 along the score line 31.

30 A second merchandise-retaining and supporting insert C may be positioned within the box if the merchandise so requires. This insert C may be formed from a single blank of paperboard material, as shown in Fig. 3, and comprises a merchandise-supporting platform 40 having side flanges 41 hinged thereto along the score lines 42 and end flanges 43 hinged thereto along the score lines 44. The side flanges 41 and the end flanges 43 are generally of less depth than the side flanges 26 and end flange 28 of the insert B, so that 35

40 when positioned in the box, as shown in Fig. 10, platform 40 will be spaced from the platform 21 the desired distance to properly support the merchandise M. The platform 40 is provided with one or more openings o' and o'' so shaped as to snugly receive that portion of the merchandise which projects therethrough. It is appreciated that one or more openings may be provided as the shape of the merchandise requires. As is shown in Figs. 3 and 10 for purpose of illustration only, the platform 40 is provided with an opening o' having a peripheral edge portion 40' conforming to the contour of the adjacent section of the merchandise, and another opening o'' having a peripheral edge 40'' so shaped as to conform to another section of the merchandise. The flanges 41 and 43 of the platform C are designed to rest upon the bottom wall panel 1 of the box. 45

55 In assembling the merchandise-retaining insert formed from the blank B into the erected box, the side spacing flanges 26 and the end spacing flange 28 are bent into a position substantially at right angles to the platform 21 and when in this position the spacing flanges 26 and 28 and the platform 21 are telescoped into the box, as indicated in Figs. 7 and 8 to surround the insert C, if one is used. It will be noted that the platform 21 presents an area substantially equal to the interior area of the erected box, so that the side spacing flanges 26 lie rather snugly against the inside face of the side wall panel 2 and 4 respectively, and the end spacing flange 28 lies rather snugly against the inside face of the adjacent securing flaps 9 and 11. The cover panel spacing section 22 will then lie snugly against the inside face of the securing flaps 9 and 11 at 60

65 70 75

the other end of the box, the spacing section 22 being of such type as to extend from the platform 21 substantially to the top edge of the adjacent end wall panel 3.

The merchandise M is then positioned within the box and drops into the opening o provided in the platform 21. The peripheral edge 21a of the opening o may be so shaped as to either snugly or substantially conform to the regular or irregular contour of the merchandise M, and the opening o in the platform 21 may be such size to retain the merchandise M in suspended position and out of contact with not only the bottom wall panel 1 but also the side wall panels 2 and 4 and the end wall panels 3 of the box, as indicated in Fig. 10. It will be appreciated that the merchandise M may be held in suspended position by the platform 21 by so cutting the opening o so that the peripheral edges 21a thereof engage the merchandise or the wrapping in which the merchandise is packed when partially inserted the required distance into the opening o. By slightly enlarging the opening o the merchandise M may be permitted to lie against the bottom wall panel 1, the platform 21 then serving to retain the merchandise M and its wrapping spaced from the side wall panels 2 and 4 and the end wall panels 3 only. Thus by making the opening o in the platform 21 of the proper size and shape, the merchandise M may either be held completely suspended by the platform 21 away from all of the surrounding bottom, side and end walls of the box, or it may be held spaced from only the side and end wall panels of the box as the nature and shape of the merchandise requires. 30

The platform 40 is slightly smaller than the interior cross-sectional area of the box, so that the side flanges 26 and the end flange 28 of the insert B will seat over the adjacent side flanges 41 in the adjacent end flange 43 of the platform C, as clearly shown in Fig. 10. The frictional contact between these parts retains the platforms 26 and 40 of the inserts B and C respectively in the proper position. It is appreciated that one or more inserts similar to the insert C may be positioned within the box as packing conditions require, in which event the side flanges 26 and the end flange 28 of the insert B are made deeper so as to raise the platform 21 thereof closer to the cover panel 23. Under certain conditions the insert C may be entirely eliminated and only the insert B used. 40

When the merchandise M has been properly packed within the box, the cover panel 23 is swung into position so as to cover the top of the box and the insert flap 30 attached thereto is inserted into the box so as to snugly lie against the inside face of the adjacent securing flaps 9 and 11, as shown in Fig. 10. If desired, the securing flap 30 may be of such height as to rest against the platform 21, so as to maintain the cover panel 23 in fixed spaced relation to the platform 21 and prevent the cover panel 23 at the free end thereof from being telescoped into the box. Thus both the spacing section 22 and the insert flap 30 may be used to retain the cover panel 23 in proper box-covering position. The cover panel 23 is further held in fixed spaced relation to the platform 21 by the inturned lip portions 13 and 15 which it overlies. 50

It will also be appreciated that the cover panel 23 may be provided with side flanges 32, as shown in dotted lines in Fig. 7, and an end flange 33, as shown in Fig. 7, which may be suitably connected together as by a securing tab 34, or an 70

edging strip as shown in dotted line in Fig. 6, in which event the cover panel 23 may be made of such size as to overlie the top edges of one of the end wall panels 3 and the side wall panels 2 and 4 with the side flanges 32 snugly telescoping over the outside face of the adjacent side wall panels 2 and 4 and the end wall panel 31. It will thus be appreciated that the box cover may either be made as shown in full line in Fig. 7 or it may be provided with side flanges 32 and an end flange 33 as shown in dotted lines in Fig. 7.

It will be appreciated that the spacing section 22 when in position within the box braces and reinforces the adjacent end wall panel 3 as to prevent inward collapse thereof. By thus bracing one of the end wall panels 3 against inward collapse, it will be appreciated that inward collapse of the other end wall panel and the side wall panels 4 and 2 is also prevented. The spacing section 22 is prevented from inward collapse by the cover panel 33 which acts as a strut extending between the end wall panels 3.

It will be further appreciated that the merchandise-supporting platform 21, snugly fitting within the box interior, also braces the side and end wall panels so as to maintain them in erect container forming position and prevents inward collapse of the side and end wall panels, further augmenting the stiffening effect of the inturned lip portion 15 and the spacing section 22 braced and stiffened by the cover panel 23.

The shipping box herein disclosed may be used with or without the merchandise-containing insert. The box can be economically formed from a single blank of paperboard substantially without waste of paperboard material and can be economically produced and assembled by automatic machinery at a rapid production rate. The box is possessed of the advantage of being collapsible into substantially flat position so as to effect substantial economies in shipping and storage prior to use thereof. The box may be quickly erected by the user by the simple manipulation of raising the side wall panels 2 and 4, which automatically brings the end wall panels 2 and 3 into erect container-forming position. The box is adequately braced and stiffened by bending the lip portions 13 and 15 inwardly so that the side and end wall panels are maintained in erect, rigid container-forming position. Further bracing of the end wall panels may be obtained by also providing each end wall panel 3 with an inturned lip portion 17 as illustrated in dotted lines in Fig. 8. A suitable cover may be provided for the box, which cover may be constructed to telescope over the side and end wall panels, if desired.

Where the nature of the goods to be packed is such as to make it desirable to retain the same in fixed or suspended position therein, the merchandise-containing insert having the cover panel associated therewith is employed. The merchandise M may be so arranged as to be held in suspended position by the platforms 21 and 40, as shown in Fig. 10 and spaced from the bottom wall 1 and the top wall panel 23. Thus delicate merchandise is protected and cushioned against shock delivered to the bottom and cover wall panels as well as the side and end wall panels. My improved box and merchandise insert assembly may be made of any desired size for the packaging of numerous relatively fragile and delicate articles of merchandise, such as toys made from plastics, edible candy, or other material, as well as numerous other articles of merchandise which are relatively fragile and must be carefully packed

and cushioned within the container. Actual test have demonstrated that fragile articles may be packed and shipped in my improved box assembly with little or no breakage resulting and with greatly less breakage than is occasioned when similar fragile merchandise is packed in containers as heretofore constructed. The flexible platforms 21 and 40 are relatively resilient and gives when exterior strain is imposed upon the walls of the box, and, further, the merchandise-supporting platform will shift and adjust itself to external pressure applied to the box, so as to protect the delicate merchandise therein against damage. The box and its merchandise-retaining insert can be easily and quickly assembled and packed and since the cover panel is attached directly to the insert, time is saved in applying the cover to the box. It will be appreciated that the inserts B and C may be used for boxes which are not made collapsible, although the insert B is particularly adapted for use in boxes of the collapsible type, since such boxes are rather bulky and a considerable saving in shipment and storage costs can be realized by making the box collapsible.

While certain novel features of the invention have been disclosed and are pointed out in the annexed claims, it will be understood that various omissions, substitutions and changes may be made by those skilled in the art without departing from the spirit of the invention.

What is claimed is:

1. A collapsible box formed from a single blank of paperboard material including a bottom wall panel, two side and two end wall panels hinged to said bottom wall panel securing flaps connecting adjacent side and end wall panels, a lip portion hinged to each of said side wall panels adapted to be turned inwardly at right angles to the side wall panel to which it is hinged, and means for effecting substantially flat collapse of said side and end wall panels to a position overlying said bottom wall panel, said means including a fold line extending diagonally across each of said end wall panels, and a pair of converging fold lines extending diagonally across one of said side wall panels and the lip portion hinged thereto, said lip portions when turned inwardly upon erection of the box side and end panels serving to brace and stiffen the same against inward collapse.

2. A collapsible box formed from a single blank of paperboard material including a bottom wall panel, two side and two end wall panels hinged to said bottom wall panel, securing flaps connecting adjacent side and end wall panels, means for effecting substantially flat collapse of said side and end wall panels to a position overlying said bottom wall panel, said means including a fold line extending diagonally across each of said end wall panels and a pair of converging fold lines extending diagonally across one of said side wall panels, and means for retaining said collapsible side and end wall panels in rigid erect container-forming position, said last named means including a lip portion hinged to the upper edge of the side wall panel traversed by said converging fold lines which when turned inwardly to lie substantially at right angles to the side wall panel, provides a bracing strut therefor, said lip portion being traversed by converging fold lines constituting substantially straightline continuations of the converging fold lines extending across the side wall panel to which it is hinged.

3. A collapsible box formed from a single blank

- of paperboard material including a bottom wall panel, two side and two end wall panels hinged to said bottom wall panel, securing flaps connecting adjacent side and end wall panels, means for effecting substantially flat collapse of said side and end wall panels to a position overlying said bottom wall panel, said means including a fold line extending diagonally across each of said end wall panels and a pair of converging fold lines extending diagonally across one of said side wall panels, and means for retaining said collapsible side and end wall panels in rigid erect container-forming position, said last named means including a lip portion hinged to each of said end wall panels which when turned inwardly to lie substantially at right angles to its respective end wall panel provides a bracing strut therefor, each lip portion being traversed by a substantially straightline continuation of the fold line extending across the side wall panel to which said lip portion is hinged.
4. A collapsible box formed from a single blank of paperboard material including a bottom wall panel, two side and two end wall panels hinged to said bottom wall panel, securing flaps connecting adjacent side and end wall panels, means for effecting substantially flat collapse of said side and end wall panels to a position overlying said bottom wall panel, said means including a fold line extending diagonally across each of said end wall panels and a pair of converging fold lines extending diagonally across one of said side wall panels, and means for retaining said collapsible side and end wall panels in rigid erect container-forming position, said last named means including a lip portion hinged to the upper edge of each of said end wall panels which when turned inwardly provide a stiffening strut for said panels, each of said lip portions being traversed by a diagonally extending fold line constituting a substantially straightline continuation of the diagonally extending fold line traversing the end wall panel to which it is hinged.
- 45 5. A collapsible box formed from a single blank of paperboard material including a bottom wall panel, connected side and end wall panels hinged to said bottom wall panel, a lip portion hinged to one of said side wall panels adapted to be turned inwardly at right angles to the side wall panel to which it is hinged, means whereby substantially flat collapse of said side and end wall panels to a position overlying said bottom wall panel can be effected said means including a fold line extending diagonally across each of said end wall panels, each of said fold lines extending from a lower corner of the box in a straight line to the upper edge of the end wall panel, and a pair of substantially straight diagonally extending and converging fold lines traversing the side wall panel to which said lip portion is hinged, said converging fold lines each extending from the lower corner of the box diagonally across said side wall panel and lip portion to the upper edge of said lip portion, said lip portion providing means when turned inwardly upon erection of the side and end wall panels for bracing and stiffening the box.
6. A collapsible box formed from a single blank of paperboard material including, a bottom wall panel, two side wall panels and two end wall panels hinged to said bottom wall panel, a score line extending diagonally across each of said end wall panels dividing each of said end wall panels into a pair of hinged inwardly collapsing sections, a pair of converging score lines extending diagonally across one of said side wall panels dividing said side wall panel into a central collapsing section and two end collapsing sections, an unscored securing flap at each corner of the box hinged to each vertical edge of each side wall panel and secured to the adjacent section only of the adjacent end wall panel, certain of said securing flaps having a portion extending across the score line of the adjacent end wall panel and overlapping the other section but unsecured thereto, said portion being operative to brace the erected adjacent end wall panel against outward collapse.
7. A shipping carton comprising, an elongated rectangular box body including a bottom wall panel and enclosing side and end wall panels hinged to said bottom wall panel, means for connecting the enclosing panels together, and a merchandise-supporting insert formed from paperboard material comprising a merchandise-supporting platform having a merchandise retaining opening extending transversely across substantially the entire interior area of the box body, supporting flanges hinged to the sides of said platform adapted to rest against the bottom wall panel of the box body, a cover panel extending across substantially the entire open end of the box body, a spacing section hinged to one end of said platform and the adjacent end of said cover panel, said spacing section being positioned adjacent the inside face of one of said enclosing panels when in operative position within said box body, and an insert flap hinged to the other end of said cover panel and adapted to be inserted into the box body so as to lie adjacent the inside face of another of the enclosing panels of the box body.
8. A shipping carton comprising, a box body formed from a single blank of paperboard material including a bottom wall panel, enclosing panels hinged to said bottom wall panel, means connecting adjacent enclosing panels together, and means for effecting substantially flat collapse of said enclosing panels to a position overlying said bottom wall panel, said means including fold lines extending diagonally across certain of said enclosing panels, and a merchandise-supporting insert formed from paperboard material comprising a merchandise-supporting platform extending transversely across substantially the entire interior area of the box body bracing said enclosing panels against inward collapse, means for retaining said platform spaced from said bottom wall panel, and a cover for the box body hinged to said platform.
- 40 9. A shipping carton comprising, a box body formed from a single blank of paperboard material including a bottom wall panel, two side and two end wall panels hinged to said bottom wall panel, means connecting the adjacent side and end wall panels together, and means for effecting substantially flat collapse of said side and end wall panels to a position overlying said bottom wall panel, said means including fold lines extending diagonally across said end wall panels and one of said side wall panels, and a merchandise-supporting insert formed from a single blank of paperboard material comprising a merchandise-supporting platform extending transversely across substantially the entire interior area of the box body bracing said enclosing panels against inward collapse, means for retaining said platform spaced from said bottom wall panel, a cover panel for the box body, and

a spacing section hingedly connecting said cover panel to said platform.

10. A shipping carton comprising, a box body adapted to be shipped to the user in substantially collapsed position comprising a bottom wall panel, two side and two end wall panels hinged to said bottom wall panel, means connecting the adjacent side and end wall panels securely together, and means for effecting substantially flat collapse of said side and end wall panels to a position overlying said bottom wall panel, said collapsing means including fold lines extending diagonally across said end wall panels and one of said side wall panels, and a merchandise-supporting member adapted to be inserted into the erected box body by the user, said member comprising a merchandise-retaining platform extending transversely across substantially the entire interior area of the box body, said platform having a merchandise-receiving opening therein, spacing flanges hinged to said platform adapted to rest upon the bottom wall panel, a cover panel for the box body, and a spacing section hingedly connecting said cover panel to said platform.

11. A shipping carton comprising, a box body having a bottom wall panel, enclosing panels hinged to said bottom wall panel and means for connecting adjacent enclosing panels together, a merchandise-supporting insert comprising a platform having an opening therein to

receive a portion of the merchandise, flanges extending from said platform resting upon the bottom wall panel of the box, and a second merchandise-retaining insert positioned above the insert first named, said second insert comprising a platform having an opening therein to receive a portion of the merchandise, flanges extending from said platform telescoped over the flanges of the platform first-named, and a cover for the box body hingedly connected to one of said platforms.

12. A shipping carton comprising, a box body having a bottom wall panel, enclosing panels hinged to said bottom wall panel and means for connecting adjacent enclosing panels together, a merchandise-supporting insert comprising a platform having an opening therein to receive a portion of the merchandise, flanges extending from said platform resting upon the bottom wall panel of the box, and a second merchandise-retaining insert positioned above the insert first named, said second insert comprising a platform having an opening therein to receive a portion of the merchandise, flanges extending from said platform telescoped over the flanges of the platform first-named, a cover panel for the box body, and a spacing section hingedly connecting said cover panel to the platform of said second-named insert.
